UNITED STATES PATENT OFFICE.

EZRA S. SMITH, OF ATTLEBORO, MASSACHUSETTS, ASSIGNOR TO R. F. SIMMONS COMPANY, A COPARTNERSHIP CONSISTING OF JOSEPH L. SWEET AND HAROLD E. SWEET, OF ATTLEBORO, MASSACHUSETTS.

DESIGN FOR A BRACELET OR SIMILAR ARTICLE.

Application filed April 9, 1926. Serial No. 17,232. Term of patent 3½ years.

To all whom it may concern:

Be it known that I, EZRA S. SMITH, a citizen of the United States of America, residing in Attleboro, in the county of Bristol and Commonwealth of Massachusetts, have invented a new, original, and ornamental Design for Bracelet or Similar Article, of which the following is a specification, reference being had to the accompanying drawing, forming part thereof, in which drawing—

Fig. 1 is an elevation of a bracelet showing my new design; and

Fig. 2 is a similar view showing the bracelet in extended position.

I claim:

The ornamental design for a bracelet or similar article as shown.

Signed by me at Attleboro, in the county of Bristol and Commonwealth of Massachusetts, this fifth day of April, 1926.

EZRA S. SMITH.
